MULTISTAGE FAN FOR SUCTION CLEANERS

Donald B. Tschudy, Canton, Ohio, assignor to The
Hoover Company, North Canton, Ohio, a cor-
poration of Ohio

Application December 7, 1950, Serial No. 199,689

18 Claims. (Cl. 230—117)

1

This invention relates to a multi-stage motor-fan unit for suction cleaners in which the usual interstage separator between the two stages of the fan is dispensed with and the necessary passages are formed in the main fan casing itself.

According to the present invention the fan casing also forms a housing for the commutator of the motor and the discharge passage from the second stage of the fan discharges directly into the commutator housing where the air expands to cool the commutator and passes longitudinally therefrom through the entire motor to cool both the stator and the rotor.

As a result of the arrangement of the present invention the total length of the motor-fan unit is decreased appreciably without a corresponding decrease in the efficiency of the motor-fan unit as such.

According to another feature of the present invention the multi-stage fan proper is formed of a single central rotating disc having blades secured to opposite sides thereof to form the multi-stage rotor. The necessary shrouds are secured to the outer sides of the fan blades on opposite sides of the central disc to form fan eye openings.

According to the present invention an outer fan chamber is provided which discharges into ducts in the main fan casing leading to the eye of the second stage impeller on the opposite side of the main fan body. The second stage of the fan discharges into passages in the main fan casing spaced annularly from the discharge passages of the first stage, which passages lead to the commutator housing.

According to another feature of the present invention the exhaust ports leading from the two stages of the fan are provided with cut-off vanes so that the velocity head of the moving mass of air at the discharge of each stage is converted to a static pressure head so as to add its effect to the total suction head created.

Another feature of the present invention is the positioning of the expansion and exhaust chambers of the first and second stages, axially coextensive with each other, and the positioning of both pairs of air passages axially coextensive with each other and with the commutator brush housing whereby the axial depth of the motor-fan unit can be materially reduced.

According to another feature of the present invention the main fan casing forms a housing for the commutator end of the motor rotor, a support for the motor casing, a partial housing for the multi-stage fan impeller, a pair of annularly spaced arc-shaped expansion chambers and

2

a pair of annularly spaced arc-shaped exhaust chambers positioned between the expansion chambers in communication with complementary expansion chambers so that both occupy the entire annulus at the discharge side of the first stage fan. The main casing also forms a pair of annularly spaced arc-shaped expansion chambers and a pair of annularly spaced arc-shaped exhaust or static head chambers positioned between the expansion chambers in communication with complementary expansion chambers so that both occupy the entire annulus at the exhaust side of the second stage of the impeller. The second stage annulus is positioned radially inwardly of and axially coextensive with the first stage annulus. Two pairs of radially extending, annularly spaced, axially coextensive air passages are positioned axially rearwardly of the first and second stage expansion and exhaust chambers. One pair connects the exhaust chambers of the first stage to the suction side of the second stage thereof, and the other pair connects the exhaust or static head chambers of the second stage to the interior of the housing at the commutator end of the motor rotor. A pair of annularly spaced radially extending commutator brush housings are positioned axially coextensive with and between the first and second stage air passages.

30 Other objects and advantages of this invention will become apparent, as the description proceeds, when taken in connection with the accompanying drawings in which:

Figure 1 is a longitudinal cross-sectional view 35 of the multi-stage motor-fan unit of the present invention showing the air flow path from the first stage to the second stage;

Figure 2 is a front view of the motor-fan unit 40 of this invention with the front cover removed showing the first stage of the fan in section and the remainder of the unit in dotted lines;

Figure 3 is a longitudinal cross-sectional view 45 showing the air flow path from the second stage to the commutator housing;

Figure 4 is an end view of the motor unit of this invention showing the general outline of the first air passages from the first to the second stage and from the second stage to the commutator housing; and

50 Figure 5 is a cross-sectional view through the motor housing showing the motor cooling air passages.

Referring to the drawings, the reference numeral 10 represents the main casing of the fan 55 preferably in the form of an integral casting. The reference numeral 11 represents the stator

of the motor and the reference numeral 12 the end cap of the motor. The casing 10 includes a forwardly bulged housing 13 for the commutator 14, the rotor 15 being mounted for rotation on bearings 16 and 17 mounted in the housing 13 and end cap 12 respectively.

The rotor shaft 18 extends forwardly through the housing 13. A fan generally indicated by the reference numeral 20 is secured to shaft 18 by means of a nut 19. The fan 20 comprises a main sheet metal disc 21 having first and second stage fan blades 22 and 23, respectively, secured to the front and rear sides thereof. Annular shrouds 24 and 25 are secured to the outer sides of the blades 22 and 23, respectively. As shown, the blades 22 and 23 are of arcuate formation and are curved to trail in the direction of rotation.

At the discharge of the first stage the fan casing 10 is divided annularly into two expansion chambers 26 and two exhaust or static head chambers 27 which together occupy substantially the entire annular extent of the casing at that radius. Radially inward of the expansion chambers 26 and 27 the casing 10 is again divided annularly into two expansion chambers 28 and two exhaust or static head chambers 29 which also occupy substantially the entire annular extent of the casing 10 at that radius. Spaced axially rearward of the expansion chambers 26 and 28 and the exhaust chambers 27 and 29 the main casing 10 is divided annularly into pairs of radially extending air passages 30 and 31 and a pair of housings 32 for the commutator brush holders 33 which together occupy substantially the entire annular extent of the casing 10 at that axial position.

The exhaust chambers 27 and 29 communicate with the expansion chambers 26 and 28 respectively by way of ports 26' and 28' respectively.

Adjacent the commutator housing 13 the radial passages 30 communicate with ports 34 leading to the eye 35 of the second stage of the fan. Ports 36 extend through the wall of the forwardly bulged housing 13 and communicate with radial passages 31 leading from the exhaust of the second stage of the fan.

A cover plate 38 having a fan eye 39 cooperates with the main fan casing 10 to form the first stage fan chamber and the expansion and exhaust chambers 26 and 27, the casing 10 being extended outwardly at 40 to prevent bypassing of air through port 26'.

The stator 11 is enclosed in a casing 41 clamped between the main casing 10 and the end cap 12. Stator coils 42 are wound on the poles 43 of the stator 11. The stator 11 does not completely fill the casing 41 whereby openings 44 are formed for the circulation of air thereover. Openings 45 in which the coils 42 are wound also provide for air circulation through the interior of the motor.

At the junction of the expansion chambers 26 and the exhaust chambers 27 and at the junction of the expansion chambers 28 and the exhaust chambers 29 the main casing is provided with extensions to form cut-off vanes 46 and 47 respectively, for a purpose to be explained hereinafter.

Operation

Upon energization of the motor the fan 20 is rotated at high speed. The first stage vanes 22 draw air inwardly through the fan eye 39 and discharge it into the expansion chambers 26 at a high velocity. The cut-off vanes 46 will pre-

vent the high velocity air from by-passing chambers 27. The high velocity air will impinge against the cut-off vanes 46 and the velocity head will be changed into a static head in the chambers 27 resulting in a net increase in the suction head produced by the first stage of the fan.

From the expansion chambers 26 the air will pass through chambers 27, radial passages 30 and ports 34 to the eye 35 of the second stage of the fan 20. The second stage blades 23 will add to the velocity head of the air stream and discharge it into expansion chambers 28. The high velocity air impinges against the cut-off vanes 47 and the velocity head is changed to a static head in chambers 29 as in the first stage to add to the net suction head produced.

The air then passes through radial passages 31 and ports 36 into the commutator housing 13 where it expands to cool the commutator 14. The air then passes backwardly through the passages 44 and 45 to cool the rotor 15 and stator 11 and is discharged through openings in the end cap 12.

The present invention is particularly suited for use in suction cleaners. The motor-fan unit can be made considerably shorter than in the ordinary multi-stage fan. In addition, the commutator can be positioned very close to the front bearing so as to have better running characteristics and so that it will be maintained in a much cooler condition than if positioned at the opposite end of the motor-fan unit.

While I have shown and described but a single modification of my invention it is to be understood that that modification is to be taken as illustrative only and not in a limiting sense. I do not wish to be limited to the specific structure shown and described but to include all equivalent variations thereof except as limited by the scope of the claims.

I claim:

1. In a multi-stage fan for pumping a gaseous medium, a main fan casing; a rotatable shaft journaled in said casing and having one end extended beyond the front face thereof; a fan impeller secured to the extended end of said shaft; said impeller comprising a centrally positioned circular disc having centrifically acting impeller blades secured to the opposite sides thereof; and means secured to said casing and operating in cooperation therewith and with said impeller for forming a multi-stage fan; said means, casing and impeller being arranged to form at least one expansion chamber at the exhaust side of the first stage of said impeller, to form a static head chamber for the first stage of said impeller in communication with said expansion chamber, to form ducts communicating with said static head chamber and leading to the suction side of the second stage of said impeller, to form at least one expansion chamber at the exhaust side of the second stage of said impeller, to form a static head chamber for the second stage of said impeller in communication with the expansion chamber of the second stage of said impeller and to form exhaust ducts in communication with the static head chamber of the second stage of said impeller.

2. In a fan according to claim 1 in which the expansion chamber and static head chamber of the first stage of said impeller are positioned radially outwardly of the expansion chamber and static head chamber of the second stage of said impeller and in axial alignment therewith.

3. In a fan according to claim 2 in which each of said static head chambers is positioned an-

nularly of its corresponding expansion chamber and in axial alignment therewith.

4. A motor-fan unit comprising; an integrally formed frame having a central opening; a motor stator supported on one side of said frame; a motor rotor rotatably supported by said frame and stator; said rotor having a shaft extended through said central opening; a fan impeller carried by the extended end of said shaft; said fan having a set of radially extending blades on each side thereof so as to form a multi-stage impeller with the inlet sides of the stages facing in opposite directions; means on said frame forming a fan eye and a casing for the outer set of blades; said frame being formed with a first expansion chamber for receiving air from the exhaust side of the outer set of blades, a first passage leading from the first expansion chamber to the rear of said impeller and communicating with the suction side on the inner set of blades, a second expansion chamber for receiving air from the inner set of blades and a second passage leading from said second expansion chamber to said central opening so as to direct air over said rotor and stator.

5. In a multi-stage fan, a cylindrical body having a forwardly bulged front wall, a shaft mounted for rotation in said wall with one end thereof extended forwardly beyond said wall, a fan impeller secured to the extended end of said shaft for rotation therewith, said impeller including a circular disc having fan blades secured to each of its opposite faces and annular fan eye forming shrouds secured to the outer edges of said blades, said impeller and body cooperating to form first and second stages of a multi-stage fan, a first pair of arc-shaped annularly spaced expansion chambers formed in said body at the periphery of the first stage of said impeller, a first pair of arc-shaped annularly spaced static head chambers formed in said body each annularly spaced from and communicating with the adjacent of said expansion chambers, a first pair of radially extending annularly spaced air passages formed in said body each communicating in its outer end with the corresponding of said first static head chambers and at its inner end with a fan eye of the second stage of said impeller, a second pair of arc-shaped annularly spaced expansion chambers formed in said body at the periphery of the second stage of said impeller, a second pair of arc-shaped annularly spaced static head chambers formed in said body each annularly spaced from and communicating with the adjacent of said second expansion chambers, a second pair of radially extending annularly spaced air passages formed in said body each communicating at its outer end with a corresponding one of said second static head chambers and at its inner end with a port formed in said body and communicating with the interior of the chamber formed by said forwardly bulged front wall.

6. In a multi-stage fan according to claim 5 in which said first expansion and static head chambers are axially coextensive with each other and together form a complete annulus at the discharge side of the first stage of said impeller.

7. In a multi-stage fan according to claim 6 in which said second expansion and static head chambers are axially coextensive with each other and with said first expansion and static head chambers and are positioned radially inwardly of the latter.

8. In a multi-stage fan according to claim 7 in which said first and second air passages are

axially coextensive with each other and are positioned axially rearward of said first and second expansion and static head chambers.

9. In a multi-stage fan according to claim 7 in which said body is provided with three forwardly extending radially spaced walls which form the inner and outer walls of said first and second expansion and static head chambers.

10. In a multi-stage fan according to claim 9 in which the disc of said impeller is extended beyond the fan blades to form the front wall of said second expansion and static head chambers.

11. In a multi-stage fan according to claim 10 including a plate extending from the outer of said walls to the eye of the first stage of said impeller forming the front wall of said first expansion and static head chambers.

12. In a multi-stage fan according to claim 5 in which said first and second air passages are axially coextensive with each other and are axially spaced rearwardly of said first and second expansion and static head chambers.

13. A multi-stage motor-fan unit comprising; an integrally formed main body including a transverse wall separating the fan chamber from the motor chamber, a rearwardly extending cylindrical wall and three forwardly extending radially spaced annular walls; a motor casing secured to the rear edge of said rearwardly extending wall, a motor end cap secured to the rear end of said casing, a motor stator positioned centrally within said casing, a shaft carrying a motor rotor including a commutator rotatably mounted in bearings located centrally in said transverse wall and said end cap respectively, said commutator being positioned at the end of said shaft adjacent said transverse wall, said shaft being extended forwardly beyond said transverse wall and having a multi-stage fan impeller secured thereto, said impeller having first stage fan blades secured to its front face and second stage fan blades secured to its rear face; said body being formed with at least one first stage discharge chamber between the outer and inner of said forwardly extending walls and communicating with the exhaust side of the first stage of said fan, with at least one first stage radially extending air passage communicating at its outer end with the first stage discharge chamber and at its inner end with the suction side of the second stage of said fan, with at least one second stage discharge chamber between the inner and intermediate of said forwardly extending walls and communicating with the discharge side of the second stage of said fan, and with at least one second stage radially extending air passage communicating at its outer end with said second stage exhaust chamber and at its inner end with the interior of the motor chamber at the commutator end thereof.

14. A multi-stage motor-fan unit according to claim 13 in which said body is formed with at least one first stage expansion chamber between the outer and intermediate of said forwardly extending walls and with at least one second stage expansion chamber between the inner and intermediate of said forwardly extending walls, and with said first and second stage expansion chambers communicating at one end with the exhaust of the first and second stages of said fan respectively and at the other end with the first and second stage exhaust chambers respectively.

15. A multi-stage fan unit according to claim

13 in which said first and second stage air passages are coextensive with each other axially of said shaft and annularly spaced from each other and said body is formed with commutator brush housings annularly between said passages.

16. An article of manufacture in the form of a casing for use in forming the main body of a multi-stage motor-fan unit comprising; a cylindrical body having a forwardly bulged transverse wall, a rearwardly extending cylindrical wall of less diameter than said body and three forwardly extending cylindrical walls spaced radially from each other; said transverse wall having a shaft bearing receiving opening in the bulged portion thereof and forming a housing for receiving the commutator end of a motor rotor; said rearwardly extending cylindrical wall forming a support for a motor casing; a first pair of arc-shaped annularly spaced expansion chambers formed in said body between the intermediate and outer of said forwardly extending cylindrical walls, a first pair of arc-shaped annularly spaced exhaust chambers formed in said body between the intermediate and outer of said forwardly extending walls and lying annularly between and axially coextensive with said first pair of expansion chambers, a first pair of radially extending annularly spaced air passages formed in said body spaced axially rearwardly of said first expansion and exhaust chambers, a second pair of arc-shaped annularly spaced expansion chambers formed in said body between the inner and intermediate of said forwardly extending walls axially coextensive with said first expansion and exhaust chambers, a second pair of arc-shaped annularly spaced exhaust chambers formed in said body between the inner and intermediate of said forwardly extending walls lying between and axially coextensive with said second pair of expansion chambers; a second pair of radially extending

5 annularly spaced air passages formed in said body between and axially coextensive with said first pair of air passages, each of said exhaust chambers communicating with an expansion chamber and each of said air passages communicating with an exhaust chamber, outlet ports formed in said body for said first air passages extending through said transverse wall radially outwardly of said bearing receiving opening and outlet ports formed in said body extending through the side walls of the bulged portion of said transverse wall immediately to the rear of said bearing receiving opening.

10 17. An article of manufacture according to claim 16 in which the intermediate and inner of said forwardly extending walls are provided with a cut-off vane at the junction between said expansion and exhaust chambers.

15 18. An article of manufacture according to claim 16 in which said body is formed with radially extending commutator brush housings between each set of first and second air passages.

DONALD B. TSCHUDY.
